(57) **CLAIM**

The ornamental design for a leveling block wheel chock, as shown and described.

DESCRIPTION

FIG. 1 is a front, top right perspective view of a leveling block wheel chock according to the invention;

FIG. 2 is a right elevational view according to the invention; and,

FIG. 3 is a left elevational view according to the invention; and,

FIG. 4 is a front elevational view according to the invention; and,

FIG. 5 is a rear elevational view according to the invention; and,

FIG. 6 is a top plan view according to the invention; and,

FIG. 7 is a bottom plan view according to the invention; and,

FIG. 8 is a back, bottom left perspective view according to the invention.
